UNITED STATES PATENT OFFICE.

FERRY F. HILL, OF BALTIMORE, MARYLAND, ASSIGNOR TO MALCOLM W. HILL, OF BALTIMORE, MARYLAND.

BRUSH AND MOP HOLDER.

1,391,111.

Specification of Letters Patent. Patented Sept. 20, 1921.

Application filed December 14, 1920. Serial No. 430,624.

To all whom it may concern:

Be it known that I, FERRY F. HILL, a citizen of the United States, residing at Baltimore, State of Maryland, have invented certain new and useful Improvements in Brush and Mop Holders, of which the following is a specification.

This invention relates to brush and mop holders, and it comprises a handle, a brush holder pivotally mounted on one side of the handle, a mop support arranged on the opposite side, said mop support comprising a substantially rectangular frame pivoted to said handle intermediate its ends, a mop secured to the outer end of said frame, a bracket arranged on said handle and spaced from said frame, and rotatable means arranged in said bracket and adapted to receive the other end of said mop.

In the present invention, I have provided a very simple support for a scrubbing brush and mop, whereby the brush may first be employed for scrubbing the floor and the mop may then be used for mopping. The brush is so mounted that it may be brought into operative position, being retained in position by a portion of the mop supporting structure. When the brush is being used, the mop is arranged on the upper side of the handle out of the way.

When the mop is to be employed, the brush may be swung upwardly away from the handle and the mop placed in proper position by applying a slight pressure to the outer end of the mop support, thus eliminating the necessity of handling the mop by the operator. The inner end of the mop is supported in a rotatable holder, whereby the mop may be wrung when desired.

In the accompanying drawings, I have shown several embodiments of the invention. In this showing:

Figure 1 is a perspective view showing the mop in operative position.

Fig. 2 is a side elevation showing the brush in operative position,

Fig. 3 is a sectional view on line 3—3 of Fig. 2,

Fig. 4 is a transverse sectional view through the mop supporting frame and handle.

Fig. 5 is a perspective view showing a slightly modified type of brush and mop holder,

Fig. 6 is a side elevation of the form shown in Fig. 5, showing the position of the mop during wringing, and,

Fig. 7 is a detail view on line 7—7 of Fig. 6.

Referring to Figs. 1 to 4 of the drawings, the handle 1 is of the usual construction and may be made of any suitable material. The pivot pin or bolt 2 is arranged transversely of the handle near its lower end. A bracket comprising a pair of spaced arms 3 is pivotally mounted on this pin, the lower ends of the arms being extended outwardly, as at 4, and connected to each other by a transverse portion 5. Enlargements 6 are provided at each side of the supporting member. A substantially rectangular mop supporting frame is arranged in the supporting member. As shown, the mop supporting frame is made of wire or any other suitable material, provided with substantially parallel front and rear sections 7 and 8. These sections are connected by longitudinal sections 9, which, as shown, pass through the enlargements 6 of the supporting member.

A brush holder is also pivoted on the pivot pin 2. The brush holder comprises a pair of substantially parallel arms 10, the ends of which are coiled, as at 11, and adapted to surround the pivot pin. These arms are off-set, as at 12, whereby the brush arranged

on the pivoted member will be in a horizontal position or parallel to the floor when the handle is in the inclined position, illustrated in Fig. 2 of the drawings. The ends of the arms are extended outwardly, as at 13, and connected by a transverse member 14, slightly spaced from the members 13. A brush 15 is secured to the brush holder by

means of screws 16, arranged in the space between the members 13 and 14. It will be readily seen that the brush may be removed when desired, and replaced by a new one. A bracket 17 is pivoted to the handle by pin 18 (see Fig. 3) and spaced from the end of the handle. This bracket is shaped to form a bearing 18', in which may be arranged a bushing 19, of brass or other suitable material.

A rod 19' is rotatably mounted in this bushing, the inner end of the rod being shaped to form an operating crank 20. The outer end of the rod is arranged substantially triangular and is adapted to receive the inner end of a mop 22, the outer end of

which is secured to the front member or the toe of the mop supporting frame.

In the form of the invention shown in Figs. 5 to 7 of the drawings, the brush and mop holder are constructed of a single piece of wire, or other suitable material. As shown, the forward end of the mop is supported by a transverse portion 23, the ends of which are extended rearwardly, as at 24, at substantially right angles, and thence inwardly, as at 25, to form a rear member or heel of the mop supporting frame. The rear transverse portions 25 extend inwardly to a point slightly spaced from each other, and the wire is then brought forwardly, as at 26, and is provided with off-sets 27 which are shaped to receive the pivot pin 2, whereby the brush and mop supporting member is mounted or arranged on each side of the handle with the pivot pin passing therethrough. The ends of the wire member are extended forwardly and slightly off-set, as at 28, the terminals being coiled, as at 29, for the reception of screws 30, whereby the brush 31 is secured thereto.

In the form of the invention disclosed in Figs. 5 to 7, the rear end of the mop is supported in the same manner as in the first form disclosed. In each form of the invention, it is necessary to limit the forward movement of the bracket 17 whereby the mop may be maintained in operative position when desired. For this purpose, I employ a fastening member 32, comprising a pair of spaced arms, slightly diverging from each other. The inner ends of the arms are arranged close enough to each other to form a seat for the head of a screw 33, whereby the member is secured to the handle. The terminals of the arms are extended rearwardly, as at 34, and are adapted to receive the arms of the brackets 17.

In operation, when the form of the device shown in Figs. 1 to 4 is to be used as a mop, the brush is first moved upwardly, as shown in Fig. 1, to its extreme position, whereby it will not interfere with the operation of the mop. The mop is then stretched to form a floor engaging portion by applying upward pressure to the toe 7 of the supporting frame. This may be done by placing the forward end of the mop supporting frame against the floor and pressing downwardly. When the mop has assumed the position shown in Fig. 1 of the drawings, it is ready for use. When the mop is to be wrung, the mop supporting frame is first moved to inoperative position to loosen the mop by applying pressure in the opposite direction. With the mop supporting frame in the position shown in Fig. 2 of the drawings, and the heel 8 out of engagement with the mop, the mop may be readily wrung by revolving the crank of handle 20.

When the brush is to be used, the handle is turned over and the brush holder swung on its pivot to assume the position shown in Fig. 2 of the drawings. It will be noted that the toe of the mop holder is in engagement with the back of the brush and the heel is in engagement with the handle, whereby further movement of the brush is prevented, and the brush retained in proper position.

In the form of the invention shown in Figs. 5 to 7 of the drawings, the operation is essentially the same. In this instance, the forward end of the mop and the brush are supported by the same member. When the brush is being employed, it is retained in proper position by engagement of the heel portions 25 with the handle. When the mop is being employed, the brush is positioned at the back or top of the mop and does not interfere with the operation. The mop is stretched or placed in operative position in the same manner, by applying an upward pressure to the toe of the supporting member and is released for wringing in the same manner by applying pressure in the reverse direction.

The fastening member 32 prevents the pivoted bracket 17 from moving upwardly beyond a predetermined point, and this allows the mop to be arranged in operative position when pressure is applied to the toe of the mop holder.

It is to be understood that the forms of my invention herewith shown and described are to be taken as preferred examples of the same, and that various changes in the shape, size, and arrangement of parts may be resorted to without departing from the spirit of the invention or the scope of the subjoined claims.

Having thus described my invention, I claim:

1. A mop holder comprising a handle, a mop supporting frame pivoted thereto, a mop having its forward end secured to the front of said frame, a rotatable support for the other end of said mop, and a bracket in which said rotatable support is mounted, said bracket comprising a substantially U-shaped member pivotally mounted on said handle, the outer end of said bracket being shaped to form a bearing for said rotatable member.

2. As an article of manufacture, a brush and mop holder formed of a single piece of wire and adapted to be secured to a handle to support a brush and mop on opposite sides thereof, said holder comprising a forward portion to which the end of a mop may be secured, a pair of arms arranged substantially at right angles thereto, each of said arms being extended substantially parallel to said forward portion and toward each other to form the rear portion of the

mop frame, said arms being extended forwardly and provided with means intermediate the front and rear portion to secure said holder to a handle, the terminals of 5 said arms being off-set from the plane of the holder and provided with means for securing a brush thereto.

3. A mop holder comprising a handle, a mop supporting frame pivoted thereto, a 10 mop having its forward end secured to the front of said frame, a rotatable support for the rear end of said mop, a bracket in which said support is mounted, said bracket com-

prising a substantially U-shaped member, pivotally mounted on said handle, the outer 15 end of the bracket being shaped to form a bearing for said supporting member, and means for limiting the forward movement of said bracket.

In testimony whereof I affix my signature 20 in presence of two witnesses.

FERRY F. HILL.
